CLAIM

The ornamental design for a compact disc rack, as shown and described.

DESCRIPTION

FIG. 1 is a front elevational view of a compact disc rack showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a left side elevational view with the legs shown in a folded or closed condition;

FIG. 8 is a right side elevational view with the legs shown in a folded or closed condition;

FIG. 9 is a front elevational view of an alternative embodiment thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a left side elevational view with the legs shown in a folded or closed condition; and,

FIG. 16 is a right side elevational view with the legs shown in a folded or closed condition.
